UNITED STATES PATENT OFFICE.

HAMILTON B. SPARKS, OF TERRE HAUTE, INDIANA.

STOVEPIPE ANCHOR, FLUE THIMBLE, AND FLUE STOPPER.

Application filed February 24, 1922. Serial No. 538,865.

To all whom it may concern:

Be it known that I, HAMILTON B. SPARKS, a citizen of the United States, residing at Terre Haute, in the county of Vigo and State of Indiana, have invented certain new and useful Improvements in a Stovepipe Anchor, Flue Thimble, and Flue Stopper, of which the following is a specification.

The present invention relates to a flue stop and stove pipe thimble combined and has for its principal object to provide means for mounting a stove pipe thimble in a flue opening so that the same may be firmly held therein and readily removed when so desired.

Another object of the invention is to provide a stove pipe thimble combined with a flue stop and means whereby these parts may be detachably secured together.

A still further object of the invention is to provide simple and efficient means for holding the stove pipe thimble in place, said means being capable of economical manufacture, reliable in operation and well adapted to the purpose for which it is designed.

With the above and numerous other objects in view, the invention relates to certain novel features of construction, and the combination and arrangement of parts as will be hereinafter more fully described and claimed.

Referring to the drawings in detail it will be seen:

Figure 1 is a front elevation of a flue stop showing the same in place,

Figure 2 is a transverse section therethrough taken on the line 2—2 of Figure 1 looking in the direction of the arrow,

Figures 3 and 4 are transverse sections taken on the lines 3—3 and 4—4 of Figure 2 looking in the direction of the arrows,

Figure 5 is a view similar to Figure 2 showing an elbow substituted for the flue stop,

Figure 6 is a transverse section taken therethrough on the line 6—6 of Figure 5 looking in the direction of the arrow,

Figure 7 is an elevation of the elbow coupling device,

Figure 8 is a similar view taken at right angles to Figure 7, and

Figure 9 is an elevation of the flue stop.

Referring to the drawings in detail it will be seen that 1 designates a stove pipe thimble which is situated in the flue opening 2 and is provided at its front end with a right

angularly extending annular flange 3 that is adapted to fit against the outer surface of the wall in which the flue opening 2 is situated. A bar 4 is spanned transversely of the thimble 1 adjacent its rear end being fixed to the pipe by means of the rivets 5 passing through the right angularly extending apertured lips 6. This bar 4 is provided with a central aperture through which extends the rod 7 so as to be rotatable therein. A stop block 8 is provided on the rod 7 on one side of the bar 4 and a stop pin 9 is situated on the other side thereof so as to prevent sliding of the rod 7. The inner end of this bar is threaded while the outer end thereof is provided with an operating handle 11. Upon the threaded end of the rod 7 there is mounted a nut 13 which is provided with a series of spaced radially extending ears 14 which are arranged in pairs so as to pivotally receive therebetween the links 15 to which are connected the auxiliary arms 16 attached to the outer terminal of the main retaining arms 17. These main retaining arms 17 are fixed to the thimble 1 adjacent its inner end and their outer ends extend so as to terminate adjacent the inside of the wall in which the flue opening 2 is provided. These terminals of the main arms 17 are provided with angular extensions 18 that are adapted to engage the inside of the wall as is shown to advantage in Figure 2 for holding the thimble 1 within the flue opening 2. From the construction thus far described it will be seen that by rotating the rod 7 the nut 13 may be moved toward or away from the bar 4. When this nut 13 is moved away from the bar 4, the terminals of the main arms 17 are forced away from each other so as to place the angular extensions 18 in engagement with the inner face of the wall in which is provided the flue. When it is desired to remove the thimble 1 the nut 13 is moved toward the bar 4 thereby bringing the terminals of the main arms 17 toward each other and releasing the angular extensions 18 from engagement with the wall whereby the thimble may be pulled out of the flue opening 2 as will be readily understood.

Intermediate the ends of the thimble 1 there are provided a plurality of inwardly extending pins 20 which are preferably disposed in diametrically opposite pairs and in the present illustration only one pair is shown by way of example and preference.

The flue stop 21 is provided with a cylindrical body portion being closed at one end by a plate 22 which extends beyond the periphery of the cylindrical body portion 5 of the stop forming a flange 23. This plate is provided with a grip member 24 so that the stop may be moved in and out of the thimble 1. At the open end of the cylindrical body of the stop 21 I have provided 10 a plurality of bayonet slots 25 which are arranged in pairs and are disposed in diametrically opposite relation to each other for engagement with the pins 20 and thus this stop 21 may be held in fixed relation to the 15 thimble 1 as will be readily understood.

When it is not desired to use the flue stop 21 but it is desired to use an elbow 26 so that a stove pipe may be attached thereto and supported thereby, I use a coupling 20 member 27 which is constructed of a cylindrical body portion or thimble having bayonet slots 28 at one end engageable with the pins 20 in the same manner as was set forth in conjunction with the stop 21 and 25 its slots 25. This coupling is provided with a semi-annular slit 29 adjacent its forward end so as to form jaw sections 30 which are slightly separated as at 31. The terminals of these jaw sections are provided with 30 brackets 32 having upstanding or outwardly extending apertured members for receiving the bolt 34 whereby the jaws 30 may be brought together by means of a nut 35 threaded on the bolt. In assembling the 35 elbow in connection with the coupling the jaws 30 are separated and the elbow is inserted into the coupling as is illustrated in Figure 5. The nut 35 is then tightened on

the bolt 34 so as to bring the jaws together, thereby clamping the coupling in engagement with the elbow 26 and holding the same firmly in place. 40

Having thus described my invention what I claim as new is:—

1. In combination, a stove pipe thimble, 45 means associated with the thimble for engaging a stove pipe, a plurality of resilient arms extending therefrom and terminating in angular extensions, a plurality of auxiliary arms attached at one end to the terminals of the first mentioned arms, a bar extending transversely of the thimble, a threaded rod rotatable in the bar, a nut on the threads of said rod, and means for connecting the auxiliary arms to the nut. 50

2. In combination, a stove pipe thimble, 55 means associated with the thimble for engaging a stove pipe, a bar extending transversely of the thimble and fixed thereto and provided with a centrally disposed aperture, 60 a rod extending through said aperture so as to be rotatably mounted therein, means for preventing sliding of the rod, said rod provided with threads, a nut mounted on said threads, a plurality of links mounted on said 65 nut, a plurality of resilient arms attached at one end to the thimble and their other ends terminating in angular extensions, and auxiliary arms connecting the ends of the resilient arms with the links. 70

In testimony whereof I affix my signature in presence of two witnesses.

HAMILTON B. SPARKS.
